US0D1106092S

(12) **United States Design Patent** (10) **Patent No.:** **US D1,106,092 S**
(45) **Date of Patent:** **** Dec. 16, 2025**

(54) **CONTROLLER FOR CAPACITIVE PANEL**

(71) Applicant: **Shenzhen Unilution Lighting Co., Ltd.**, Shenzhen (CN)

(72) Inventor: **Jiyun Yan**, Lvlhang (CN)

(**) Term: **15 Years**

(21) Appl. No.: **35/523,373**

(22) Filed: **Nov. 26, 2024**

(80) **Hague Agreement Data**

Int. Filing Date: **Nov. 26, 2024**

Int. Reg. No.: **DM/242639**

Int. Reg. Date: **Nov. 26, 2024**

Int. Reg. Pub. Date: **Dec. 20, 2024**

(51) **LOC (15) Cl.** **14-03**

(52) **U.S. Cl.**

USPC **D13/168**; D14/218

(58) **Field of Classification Search**

USPC D14/155, 218; D13/168; D10/49

CPC B42D 9/04; G06F 3/0485; H04N 21/42204

(57) **CLAIM**

The ornamental design for controller for capacitive panel as shown and described.

DESCRIPTION

1. Controller for capacitive panel

1.1 : Perspective

1.2 : Front

1.3 : Back

1.4 : Left

1.5 : Right

1.6 : Top

1.7 : Bottom

The broken lines in the drawings depict portions of the controller for a capacitive panel that form no part of the claimed design.
